H. B. SMITH.
SNAP FASTENER DEVICE,
FILED DEC. 5, 1921.

Paul M. Hunt

John W. Smith

Henrietta B. Smith
INVENTOR
BY *Victor J. Evans*
ATTORNEY

UNITED STATES PATENT OFFICE.

HENRIETTA BREWSTER SMITH, OF CHARLESTON, SOUTH CAROLINA.

SNAP-FASTENER DEVICE.

Application filed December 5, 1921. Serial No. 520,115.

To all whom it may concern:

Be it known that I, HENRIETTA B. SMITH, a citizen of the United States, residing at Charleston, in the county of Charleston and State of South Carolina, have invented new and useful Improvements in Snap-Fastener Devices (Case B), of which the following is a specification.

My present invention has reference to garment fasteners and may be considered in the nature of an improvement upon the snap fastener device upon which I received United States Letters Patent No. 1,345,267, granted June 29, 1920.

15 The invention further resides in the novel construction, combination and operative association of elements set forth in the following description and claims.

In the drawings:—

20 Figure 1 is a plan view of the female or socket member of a snap fastener, constructed in accordance with this invention.

Figure 2 is a plan view looking toward the under face of the improvement.

25 Figure 3 is a sectional view on the line 3—3 of Figure 2.

Figure 4 is a modified fragmentary plan view of the construction disclosed in Figure 2, but illustrating a modified means for sustaining the spring member on the fastener.

30 Figures 5, 6 and 7 are fragmentary plan views with parts broken away and parts in section, illustrating modified forms of spring rings and means for sustaining the rings on the fastener.

35 As disclosed by the drawings the improvement includes a body plate 1 and a rim 2. The rim is triangular in plan and is preferably straight or flat. The rim 2, at the angle corners thereof is notched, as at 3. The body plate is hexagonal in plan, all of the edges thereof being preferably straight or flat and received in the straight rim 2. The edges of the body plate being in contacting engagement with the rim are secured thereto in any desired or preferred manner, while the spaces 4 between the disconnected edges of the body plate and the angle corners of the rim provide thread pockets, the threads 45 which attach the eyelet to the garment being also received in the depressed portions 3 of the rim.

The body plate is centrally formed with a round opening 5, the said plate being provided with portions which project into the opening, and the said plate being slotted in a line with the edges of these portions. These portions are indicated by the numeral 6, and the same are bent or otherwise rounded upon themselves to provide cross sectionally rounded pockets 7 for a split ring 8. As the mouths of the pockets 7 are arranged to communicate with the openings in the plate, it will be apparent that the split ring will be partly projected into the said opening, and therefore the same may readily engage with the headed male member of the garment fastener which is designed to pass through the opening 5 in the female member herein described. The split ring 8 is preferably elliptical in plan, while the headed male member (not shown) may be either round or triangular in plan.

In Figures 4, 5, 6 and 7 of the drawings, the construction is substantially similar to that above described, except that in Figures 5, 6 and 7, the split ring received in the pockets in the body plate is so made that when contacted it will project into the opening a greater distance than will the split ring 8 in Figure 4.

In Figures 1, 2, 3 and 4 of the drawings, the pockets are formed at the central opening thereof by substantially U-shaped projections.

It is thought that the foregoing description, when taken in connection with the drawings will fully set forth the construction and operation of the improvement.

Having described the invention, I claim:—

1. In a garment fastener, a socket member comprising a body having a central opening therethrough, the wall of which having, at spaced intervals cross sectionally rounded portions which provide pockets, and a split ring received in said pockets and projected into said opening.

2. In a garment fastener, a socket member including a rim which is substantially V-shaped in plan and which has its pointed corners notched, a hexagonal plate constituting the body of the socket having three of the edges thereof received in the rim and the spaces between the remaining edges and

the notched portions of the rim providing thread eyes, said body plate having a central round opening and having portions which project into the opening, the said body being slotted in a line with the ends of the said portions to permit of the said portions being rounded upon themselves to

provide pockets which communicate with the opening, and a split elliptical ring received in the pockets and partly projecting into the opening, as and for the purpose set forth.

In testimony whereof I affix my signature.
HENRIETTA BREWSTER SMITH.
